CLAIM

I claim the ornamental design for a garment, as shown and described.

DESCRIPTION

FIG. 1 is a front perspective view of a garment, showing my new design;

FIG. 2 is a front view thereof; and,

FIG. 3 is a right side view thereof.

The dot-dash broken lines adjacent to the shaded areas define the bounds of the claim and form no part of the claimed design. The short dashed broken lines that outline the garment depict the environment associated with the claimed design, but form no part of the claimed design.
